[**] Term: **14 Years**

[57] **CLAIM**

[21] Appl. No.: **29/083,481**

I claim the ornamental design for a combined textured sleeve with stanchion, as shown and described.

[22] Filed: **Feb. 11, 1998**

DESCRIPTION

[60] Continuation-in-part of application No. 29/054,342, May 30, 1996, which is a division of application No. 29/019,652, Mar. 7, 1994, Pat. No. Des. 374,941.

FIG. 1 is an exploded perspective view of a combined textured sleeve with stanchion according to the invention, the stanchion is broken on the end for ease of illustration, however the stanchion is the same length as the textured sleeve portion;

[51] **LOC (7) Cl. 25-01**

FIG. 2 is a side elevational view thereof with the textured sleeve in full position outside the stanchion; and,

[52] **U.S. Cl. D25/126**

FIG. 3 is a sectional view thereof taken along line 3—3 of FIG. 2.

[58] **Field of Search** D25/126, 38-43, D25/16; D20/10, 41; 228/126; 256/19-34, 56-65, 43, 47, DIG. 5; 52/71, 27, 27.5, 38, 40, 728, 301, 300
